BOTTLE CAP

Arnold Perlman, Greenwich, Conn., assignor to
Helene Pessl, Inc., New York, N. Y., a corpora-
tion of New York

Application March 14, 1950, Serial No. 8,510

Term of patent 7 years

(Cl. D58—26)

To all whom it may concern:

Be it known that I, Arnold Perlman, a citizen of the United States of America, residing at Greenwich, in the county of Fairfield and State of Connecticut, have invented a new, original, and ornamental Design for a Bottle Cap, of which the following is a specification, reference being had to the accompanying drawing, forming part thereof.

In the drawing

Fig. 1 is a top plan view of a bottle cap showing my new design;

Fig. 2 is a front elevational view. The two side and rear views of the cap present the same appearance as that shown in Fig. 2; and

Fig. 3 is an exploded perspective view of the cap showing the parts thereof.

I claim:

The ornamental design for a bottle cap sub-
stantially as shown and described.

ARNOLD PERLMAN.
